UNITED STATES PATENT OFFICE.

WILLIAM GEORGE WEAGLY, OF GALION, OHIO.

FOLDING CLIP-BOARD.

SPECIFICATION forming part of Letters Patent No. 403,233, dated May 14, 1889.

Application filed June 29, 1888. Serial No. 278,545. (No model.)

To all whom it may concern:

Be it known that I, WILLIAM GEORGE WEAGLY, a citizen of the United States, residing at Galion, in the county of Crawford 5 and State of Ohio, have invented certain new and useful Folding Clip-Boards; and I do hereby declare the following to be a full, clear, and exact description of the invention, such as will enable others skilled in the art 10 to which it appertains to make and use the same.

My invention relates to that class of paper-clips which combines a support or hand-rest with a clamp for holding sheets of paper in 15 position for writing thereon, and includes the general features of a writing-tablet and a temporary binder.

The most important object of my invention is to secure a clip-board which may be folded 20 or rolled into a small compass, so as to be easily placed in a coat-pocket or other receptacle of limited capacity. I attain this object with the other features of my invention by the construction and arrangement of parts 25 shown in the accompanying drawings, in which—

Figure 1 is a perspective view of my folding clip-board complete. Fig. 2 is a perspective view of the same folded or rolled, 30 and Fig. 3 is a rear view of the clamp or paper-retaining device as applied to my clip-board.

Corresponding letters refer to corresponding parts in the several views shown.

The base of my clip-board consists of a 35 number of narrow rectangular wooden slats, A A, of uniform size, which are connected with each other and with a top slat, B, of the same thickness with the slats A, but having 40 greater width, by means of a sheet of canvas, C, which is gummed to the upper surface of the slats A and B. To the slat B is attached, by means of spiral springs s, a 45 clamp or clip, D, preferably made of metal, and having soldered thereto a wire handle, E, for turning or releasing the clamp. At the center of and screwed into the edge of the slat B is a small hook or eyelet, c, and in the edge of the bottom slat, A, is a corre-

sponding hook or eyelet, b. When the board 50 is open, an elastic band, x, in the eyelet b may be stretched around the lower end of the board, and thus keep in place the sheets of paper at that end. If not needed for this purpose, said band may be stretched under 55 the slats A and placed over the hook or eyelet c, when it will serve to keep the tablet or clip-board open. When the board is rolled or folded, the same band, by being released from the hook or eyelet c, may encircle the 60 clip-board and have both ends fastened to the eyelet b, and it will then serve to keep the board rolled.

In the manufacture of my folding clip-board, I do not confine myself to the use of 65 canvas as a facing for the slats, but may use leather or other suitable material; and instead of making the handle E of wire it may be stamped out of and be a part of the same piece of metal with the clamp D. It will 70 also readily be seen that the folding board or tablet may be used, without the clamp, as a support for sheets of paper upon which it is desired to write; nor do I confine myself 75 to wood in the manufacture of the slats A, for heavy pasteboard may be economically used and effect the same object, though not so desirable or durable as wood.

When the tablet or clip-board is flattened out, the sides of the slats A abut against each 80 other, and thus form a firm and level support for the paper laid thereon and upon which it is desired to write.

By using this device a desk or other firm flat surface on which to place the clip-board 85 may be dispensed with, as by placing the thumb and forefinger on the upper side of the clip-board and pressing it against the other fingers beneath the board the latter becomes perfectly rigid and firm. My invention is therefore especially valuable to travelers who desire to write *en route*, and who at the same time cannot conveniently carry a large tablet not capable of being folded.

Having thus described my invention, what 95 I claim as new, and desire to secure by Letters Patent, is—

1. As a new article of manufacture, a fold-

ing clip-board consisting of narrow slats flexibly connected with each other and provided with a suitable clamping device, as D, as and for the purposes set forth.

5 2. The combination, in a folding clip-board, of a series of narrow slats, a flexible facing for said slats, and a clamping device, as D, substantially as set forth.

In testimony whereof I affix my signature in presence of two witnesses.

WILLIAM GEORGE WEAGLY.
